UNITED STATES PATENT OFFICE

2,488,811

ELECTRONIC CONTROL DEVICE

Stanley D. Eilenberger, Kenosha, Wis., assignor,
by mesne assignments, to Chicago Coin Ma-
chine Co., a corporation of Illinois

Application September 20, 1943, Serial No. 503,163

3 Claims. (Cl. 315—326)

1

This invention relates to a system of electronic control, where the controlling factor is a change in the properties of the test material, as, for example, a change in the moisture content of paper. By way of further example, the instrument may also be used as a gauge in determining the ripeness of fruit, the thickness of one insulating material applied over a second insulating material, such as, for example, one or more coats of paint on wood or Bakelite, etc.

The present invention is an improvement on the invention disclosed in my co-pending application Serial Number 502,843, filed September 17, 1943, now Patent 2,428,700 issued on October 7, 1947.

The present invention makes use of feedback between two electrodes which are, in part, shielded from each other. The control voltage developed does not depend on absolute capacity change and the arrangement is such that specific control voltages are developed independent of the total mass of the test material, without actually contacting the test material and without having electrodes on opposite sides of the test material.

It is well known in the art that any electronic amplifier will oscillate if the output of said amplifier is coupled to the input of said amplifier, providing sufficient energy is fed back from the output of said amplifier to the input of said amplifier. It is also well known in the art that the frequency of oscillation will be determined by the circuit constants and that said frequency may be made to have any value desired by proper selection of said circuit constants.

As previously stated, numerous measurement systems have been based on this feedback principle, where measurements were made in terms of change of some value, such as capacity, inductance or resistance. Briefly, the present invention discloses a means for producing a feedback voltage, the value of which is a function of the properties of the test material but without the limitation implied by absolute values of capacity, inductance or resistance. This is accomplished by the use of two electrodes, one connected to the output of an amplifier and the other connected to the input of said amplifier, said electrodes being so shielded from each other that oscillation does not normally occur, with all circuit values so adjusted that for a given condition of the material under test a definite feedback voltage is available at the output terminals of the amplifier, where the value of voltage so obtained may represent a minimum, a

2

maximum or any value between said minimum or maximum voltages, this being dependent on the particular application for which the electronic control device is to be used. For this condition a small change in the property of the material undergoing test will produce a large change in control voltage.

For example, where it is desired to determine the moisture content of paper and to operate external control circuits according to the value of said moisture content, it is entirely practical to have a voltage ratio of 100:1 with a change in moisture content on the order of 1%. Continuing with this example, it may be assumed that the minimum desired moisture content is 3%, the maximum desired moisture content is 5% and the average moisture content is 4%. For this hypothetical case the control instrument may be so adjusted as to provide, for example, 10 volts control voltage for a moisture content of 4% and, without resorting to maximum sensitivity, this control voltage may rise to 15 volts for a moisture content of 5% and drop to 5 volts for a moisture content of 3%. Continuing with this hypothetical case, actual control circuits could be arranged to close at any desired fraction of 1% above or below 4%.

It is understood that the foregoing is by way of example and is not to be deemed as restrictive in scope. While the example is confined to moisture content of paper, it is understood that a similar arrangement may be used in connection with any test material where said test material changes in specific inductive capacity, surface resistivity, volume resistivity or thickness of the test material. It is understood that the thickness of the test material may be made the test factor.

This invention will be best understood in consideration of the following detailed description, in view of the accompanying drawing forming a part of the application. Nevertheless, it is understood that the invention is not confined to the disclosure, being susceptible to such changes and modifications as define no material departure from the salient features of the invention as expressed in the appended claims.

In the drawing the single figure represents a complete schematic circuit arrangement of the control instrument, including a cross section view of the test electrode assembly, and including the electronic control circuit, where that part of the schematic below the broken line X is the instrument used to develop the control voltage and that part of the schematic above the broken

line **X** is the control circuit arranged to control further external circuits.

Referring more particularly to the lower part of the figure, below broken line **X**, a typical amplifier is represented by vacuum tubes **1** and **83** and their connections. For purposes of example, both tubes are represented as tetrodes, it being understood that other forms of tubes may be used, and that any number of tubes may be used in such an amplifier arrangement. The maximum possible sensitivity is, in part, a function of the voltage gain of such amplifier and, in part, of the frequency of oscillation. In the present example, the frequency is on the order of 4000 C. P. S., this factor being largely determined by the design of iron core transformer **30**, and the voltage gain is on the order of 10,000.

Control grid **4** of vacuum tube **1** is connected through a shielded line **85** to metal electrode **41**, which is in turn partially shielded by grounded shield **43**, electrode **41** being shown in cross section with the upper plane surface unshielded. Electrode **41** is mounted in a block of insulating material **40**, preferably some material having a low dielectric constant, such as, for example, a ceramic material, or polystyrene. Grid resistors **5** and **13**, cathode resistors **6** and **14**, cathode bypass condensers **7** and **16**, screen resistors **8** and **15**, screen bypass condensers **9** and **17**, plate resistor **10** and coupling condenser **11** are all of a value normally used in the type of amplifier represented in the lower half of the figure, the actual values being largely determined by the particular tubes employed, and by the plate voltage available between negative plate voltage terminal **25** and positive plate voltage terminal **26**, this plate voltage being by-passed by condenser **18**, and preferably regulated to provide a constant voltage.

The output of vacuum tube **83** is coupled to diode rectifier **84** by transformer **30**, which has a primary winding **31** and a secondary winding **32**—**33**. Vacuum tube **84** is represented as a conventional diode having plate **34** and cathode **35**, it being understood that other forms of rectifier may be used in order to provide a direct voltage at terminals **45** and **46**. The direct voltage output of rectifier **84** appears across load resistor **22** and is by-passed by condenser **23**, this direct voltage being connected to terminals **45** and **46**, the polarity being as indicated. If desired, an indicating meter **21** may be connected in parallel with this voltage and rheostat **20** may be employed to calibrate the reading obtained on meter **21**.

Feedback voltage is taken from terminal **32** of transformer **30**, it being understood that terminals **32** and **33** are reversable, actual connection depending on the phase relationship necessary to secure oscillation. This feedback voltage is connected through condenser **36** and potentiometer **37** to electrode **42** which is in the form of a flat plate attached to the lower side of insulating block **40**, electrode **42** being shielded on the lower side by grounded shield **44**. The adjustment of potentiometer **37** is such that minimum, or zero, oscillation is obtained with no test material, as represented by **39**, in the electric field existing between electrode **42** and electrode **41**. For this condition, any test material **39** placed in the electric field will produce an increased voltage at terminals **45** and **46**.

An alternate adjustment would be for a condition where test material **39** varies between arbitrary limits. For example, test material **39** may represent paper moving at high speed in a paper

machine, where the minimum moisture content desired is 3%, the maximum moisture content desired is 5% and the average moisture content is 4%. The adjustment of potentiometer **37** for this condition may be made with a test sample **39** having a known moisture content of, for example, 4%, and, for this known moisture content, potentiometer **37** may be adjusted to develop any arbitrary voltage at terminals **45** and **46**. By way of example, this voltage may be taken as 10 direct volts and, by way of further example, it may be assumed that the voltage will increase to 15 direct volts for a moisture content of 5% and decrease to 5 direct volts for a moisture content of 3%.

This direct voltage which appears at terminals **45** and **46** is used to control two gas discharge tubes generally referred to by numerals **47** and **69**. These gas discharge tubes are so arranged as to have control characteristics of opposite polarity, where tube **47** is triggered by increased positive voltage and tube **69** is triggered by increased negative voltage, which is equivalent to decreased positive voltage.

Referring particularly to the control circuit represented by gas discharge tube **47**, suppressor grid **49** is biased negative in respect to cathode **51** by direct voltage **53**. The control voltage appears across potentiometer **52**, with polarity as indicated. The plate voltage is obtained from winding **60** of transformer **58**, primary **62** of said transformer being connected to a suitable source of voltage **38** which, for purposes of example, may be 60 cycle alternating current. Plate voltage from winding **60** is connected to plate **48** in series with current limiting resistor **59** and relay coil **55**, relay coil **55** being by-passed by condenser **54** which is designed to hold relay **55** operative during the negative half of the plate voltage cycle. Contacts **56** of relay **55** are normally open and are connected to terminals **57**, terminals **57** being further connected to external apparatus designed to correct the moisture condition, for example, terminals **57** may control the operation of a high frequency induction heating device designed to reduce the moisture content of material **39**.

For any given value of plate voltage E_{p1} , a definite positive value of grid voltage E_{g1} will be necessary to ionize gas discharge tube **47**, thus operating relay **55** and closing contacts **56** to operate the external device controlled by terminals **57**. In the example given, where the average control voltage was taken as 10 volts, the suppressor grid voltage furnished by battery **53** and the setting of potentiometer **52** are such that gas discharge tube **47** remains de-ionized. Any increase in moisture content of test material **39** will be reflected as an increase in direct voltage at terminals **45** and **46** and the direct grid voltage E_{g1} will also increase in the positive direction. The actual sensitivity of control will be determined by the setting of potentiometer **52**. Assuming that potentiometer **52** has been adjusted for a voltage regulation of 1 volt, gas discharge tube **47** will ionize when E_{g1} rises 1 volt and gas discharge tube **47** will remain ionized until this voltage E_{g1} returns to its original value, at which time gas discharge tube **47** will de-ionize on the first negative half cycle of plate voltage, thus releasing relay **55**, restoring contacts **56** to the normally open position and de-energizing the external apparatus connected to terminals **57**.

The operation of gas discharge tube **69** is identical to the operation just described for gas discharge tube **47**, except that all polarities are re-

versed, so that vacuum tube 69 will ionize on a decrease in control voltage E_{g2} , the actual sensitivity again being controlled by potentiometer 64. The operation of relay 66, condenser 68, current limiting resistor 63, contacts 67 and terminals 65 being similar to that previously described. Plate voltage E_{p2} obtained from winding 61 of transformer 68 is similar in value to plate voltage E_{p1} obtained from winding 60, any slight difference in value being unimportant as actual ionization voltage will in any event be controlled by the adjustment of potentiometers 52 and 64. The input voltage to primary 62 of transformer 58 should preferably be regulated to provide a constant voltage. Control terminals 65 are in this case designed to control external apparatus for increasing the moisture content of the test material which, for purposes of example, may be accomplished by controlling solenoid valves to increase the water content of the pulp.

The invention has been described for a condition where a minimum and maximum value of the test material was the control factor in operating external circuits in accordance with changes between said minimum and maximum values. While the moisture content of paper was used in the foregoing example, it is understood that a similar arrangement may be used with a wide variety of materials. By way of further example, a similar arrangement may be used in testing the ripeness of fruit, where the minimum and maximum values are represented by a pre-determined degree of greenness and ripeness in said fruit, and for this application the control voltage is determined largely by said degree of ripeness and is almost totally independent of actual mass of the test items, provided the design of shielded electrode assembly 41-43 is such that the electric field is confined to an area much smaller than the test item. For example, in testing oranges having a nominal diameter in the range of 2.5 to 4 inches, the electric field existing between electrodes 43 and 41 should be restricted to an area on the order of 1 inch in diameter. For this condition, actual mass will not materially affect the control voltage. By way of further example, the minimum and maximum values may well represent the distance of any object, conductive or non-conductive, from electrode 41, the average value being taken as the mean distance, with control voltages varying in accordance with minimum and maximum distances. Innumerable other applications of the invention herein disclosed will occur to those skilled in the art.

For the sake of clarity and simplicity, the invention has been described with only a minimum and maximum value represented by two gas discharge tubes as the controlled medium. It is understood that the method is applicable to a single tube for certain conditions or for a multi-

plicity of tubes for certain other conditions, wherein each tube represents a definite change in the test material, it being further understood that for certain applications this invention may be practiced without any intermediate control device as represented by the gas discharge tubes. For example, where relatively coarse control is required, the change in control voltage may well be used to operate differential relays. This method would not provide the close control possible with gas discharge tubes, where control may be realized with a voltage change of 1 volt or less. However, for certain applications, differential relays would provide economy of operation.

The above examples are for the purpose of illustrating some of the methods and means by which the broad purposes of the invention may be carried out and are not to be deemed as restrictive in any manner. Other modifications and alternatives will occur to those skilled in the art without departing from the scope of the invention as defined by the following claims.

I claim:

1. A system for testing a material with respect to a physical characteristic which changes its conductivity, said system comprising a vacuum tube amplifier having an input and an output, a pair of electrodes connected to said input and output respectively and adapted to be disposed in proximity to material to be tested, said electrodes being coupled to each other through said material with the physical state of said material determining the amount of coupling between said two electrodes, said amplifier having a sufficiently high gain so as to be unstable and being adapted to oscillate when the coupling between said electrodes exceeds a predetermined value, rectifier means for deriving a direct potential from the amplifier output in proportion to the intensity of oscillation of said amplifier and a relay system fed by said derived potential and biased to change its condition when said derived potential increases or decreases with respect to a predetermined value whereby there is material selection with reference to a predetermined conductivity.

2. The system of claim 1 wherein said relay is of the gaseous discharge tube type.

3. The system according to claim 1 wherein said relay system includes a pair of grid controlled gas discharge tubes.
